(57) **CLAIM**

We claim the ornamental design for a headrest assembly, as shown and described.

DESCRIPTION

FIG. 1 is a front perspective view of a headrest assembly embodying the present invention;

FIG. 2 is a rear perspective view of the headrest assembly;

FIG. 3 is a front elevational view of the headrest assembly;

FIG. 4 is a first side elevational view of the headrest assembly;

FIG. 5 is a rear elevational view of the headrest assembly;

FIG. 6 is a second side elevational view of the headrest assembly;

FIG. 7 is a top plan view of the headrest assembly; and,

FIG. 8 is a bottom plan view of the headrest assembly.

The broken lines shown in the drawing are for illustrative purposes only and form no part of the claimed design.
